UNITED STATES PATENT OFFICE.

CHARLES J. MARSHALL AND FRANK R. WEAVER, OF BELOIT, WISCONSIN, ASSIGNEES
TO P. B. YATES MACHINE COMPANY, OF BELOIT, WISCONSIN, A CORPORATION OF
WISCONSIN.

MILLING-MACHINE ADJUSTMENT AND QUICK RELEASE.

Application filed May 20, 1920. Serial No. 382,707.

To all whom it may concern:

Be it known that we, CHARLES J. MARSHALL and FRANK R. WEAVER, citizens of the United States, residing at Beloit, in the 5 county of Rock and State of Wisconsin, have invented certain new and useful Improvements in a Milling-Machine Adjustment and Quick Release, of which the following is a specification.

10 The invention relates to a planing, matching and finishing machine for acting upon lumber or other rough material to the end that in one passage through the machine the same shall be smooth finished on all its 15 surfaces and tongued, grooved, hollow-backed or otherwise prepared for use as ceiling, flooring or the like.

Among the features of construction characterizing the invention are improved 20 means providing for the easy and accurate adjustment of the operating parts within a wide range to adapt the same to the requirements of the work in hand; also improvements in the construction and mounting of 25 working parts whereby to effect compactness, elasticity in operation and capacity for performing superior work.

In particular, the invention provides for 30 the mounting of the several cooperating feed roll and guide-carrying members in such manner as to facilitate and insure accuracy of adjustment and to permit of quick release and withdrawal in case of emergency, as when a jamming of the stock appears imminent or for any other reason the 35 progress of the stock through the machine is to be intermittent. Other features of improvement will become apparent as the construction and operation of the machine is 40 understood.

In order that the invention may be readily understood by those skilled in the art, a preferred embodiment of the same in a wood-working machine is set forth in the 45 accompanying drawings and in the description predicated thereon. As, however, the invention is susceptible of embodiment in other varied constructional forms depending upon the material and the nature of the 50 work to be performed, the drawings and description are to be taken in an illustrative and not in an unnecessarily limiting sense.

In the drawings—

Fig. 1 is a top plan view of so much of

a milling machine as is directly concerned 55 with the present invention;

Fig. 2 is a longitudinal vertical section of the medial portion of the machine taken on the line 2—2 of Fig. 1;

Fig. 3 is a side elevation as viewed from 60 the righthand of Fig. 1;

Fig. 4 is a fragmentary transverse section on the line 4—4 of Fig. 3;

Fig. 5 is a similar section on the line 5—5 65 of Fig. 3;

Fig. 6 is a section on the line 6—6 of Fig. 5;

Fig. 7 is a fragmentary section on the line 7—7 of Fig. 1;

Fig. 8 is a detail in the nature of a sectional elevation such as might be taken on the line 8—8 of Fig. 1, with the addition of certain parts.

Fig. 9 is a plan view of that part of the 70 machine illustrated in Fig. 8; and

Fig. 10 is a section on the line 10—10 of Fig. 9.

Fig. 11 is a perspective detail illustrating 75 members of the flexible feed roller mounting in disassembled relationship.

The machine in which the present invention is embodied is of the same general type as that set forth in Patent 1,183,013 issued May 16, 1916 upon the application of Lane and Weaver; wherefore it is not deemed 80 necessary to describe in detail the features of the machine which are separate and apart from the present invention and unnecessary to a full understanding of the functioning thereof, as for instance the drive, 85 the mounting of the several cutter heads by which the two edges and two faces of the material are treated, etc.

As viewed in Fig. 1, the material enters 90 the machine from the left between the inner rolls 11 and proceeds to the right between the yielding feed rolls 12 and the fixed feed rolls 13 arranged in pairs, after which the material passes between out-rolls (not shown), and is discharged from the machine. In its passage through this particular machine, the material is hollow-backed by the cutter head 14, has its front face finished by the cutter head 15, (shown in dotted lines) and afterward automatically 95 has its two edges respectively tongued and grooved, after passing beyond the medial portion of the machine illustrated, by cut-

ter heads mounted in opposed relation below and above (not shown).

The present invention is directed particularly to the maintenance of the entering material under spring tension against a fixed guide while being acted upon by the first mentioned cutter head 14 and for quickly releasing said tension and withdrawing the housing of said cutter head in case of emergency; also means for accurately positioning and locking in place the abutment guide for the material while being acted upon by the cutter head 15, and the provision of a quick release therefor; 10 also the assemblage of the feed rolls and the yieldable mounting of one roll of each pair; also the arrangement of a yielding guide for the material as it passes from the cutter heads for dressing the front and rear 15 to the cutter heads operating upon its edges.

Having now reference to Figs. 2, 3 and 7, it will be observed that the cutter head 14 is mounted in a fixed portion 16 of the machine frame and is enclosed within a 20 housing forming an exhaust 17 for the chips. The housing 17 is pivoted at 18 and has attached eccentrically thereof at 19 a latch rod 20 carrying a loose collar 21 between which and the lock nuts 22 is a 25 spring 23. This latch rod lies within a bifurcated standard 24 against which the collar 21 bears under the tension of the spring 23, pressing the housing and the guide member 25 yieldingly towards the fixed guide 30 26. The guide 25 preferably has an obliquely arranged portion 24^a leading thereto. A retractable pin 27 is mounted in a sleeve on the housing and downwardly 35 spring-pressed for engagement in a horizontally elongated recess in a stationary frame member, serving as a stop to limit the inwardly and outwardly swinging movement of the housing. A cover plate 28 pivoted at 19 and provided with a segment slot 40 29 for the accommodation of an operating handle 30 affords means for inspecting the cutter head within the housing, but when it is desired to swing the housing upon its pivot 18 free of the cutter head the collar 45 21 may be dislodged from the standard 24 by striking the same to the right and lifting the pin 27 out of its recess in the base 50 plate thus releasing the housing.

As noted, the guide rail 24^a and 25 in 55 advance of the cutter head 14 is under the influence only of the spring 23. At the rear of the cutter head 14 is arranged another movable guide 31 opposed to the fixed guide 26, the manner of mounting of which for 60 purposes of adjustment and yielding is most clearly shown in Fig. 7 taken in connection with Figs. 1 and 3. Having reference to Fig. 7 it will be seen the guide 31 is suitably secured to the head 32 of a slide 33 65 mounted within a casing 34 and adjustably

connected by means of the bolt 35 with an arm 36 of another slide 37 within the same casting. This connection includes a nut 37^a threaded on the bolt 35 and a spring 38 disposed between the nut and the arm 36. 70 While the spring 38 tends to hold the guide 31 in its most advanced position as limited by the head of the bolt bearing upon the arm, the guide may yield under abnormal pressure against the tension of the spring 38, the shank of the bolt sliding in the arm 36. The nut 37^a serves to adjust the tension of the spring 38 as may be desired.

The extreme forward position of the guide 31 is adjusted by means of the crank 39 acting upon the screw spindle 40 threaded into the casting 34; the advancing and retracting of the screw spindle carrying with it the slide 37 and also the slide 33 through the connecting bolt and arm. 80

It is usual in machines of this type to mount the cutter heads in adjustable relation to a fixed guide rail which serves as an abutment for the material; in the present instance we fixedly mount the cutter head 90 for finishing the front face of the material and adjustably mount the guide rail for positioning the material with reference to the head and provide for locking the same in this position subject to a quick release 95 and withdrawal in emergency. This arrangement will be most readily understood by reference to Figs. 4, 5 and 6 taken in connection with Figs. 1 and 3.

Having reference to these figures, the 100 bracket 41 fixed to the machine frame carries a casting 42 having dovetail formation which serves as a guide for the slidable frame 43 which has depending side members 43^a which snugly fit against the side members 42^a of the casting 42. A clamping rod 44 threaded into 43^a at one side of 42^a extends across the casting 42 and has attached to its opposite end a lever 45 by means of which the clamping rod 44 is turned and thus releasably clamps the casting securely between the side members 43^a of the frame. Along the inner side of the frame 43 there is an upstanding edge 43^b to which is securely affixed by means of the bolts 46 a 105 guide rail 47 in opposition to the finishing cutter head 15. This frame 43 has upstanding ears 48 within which is journaled a cross shaft 49.

The casting 42 is provided in its medial 110 portion with a dovetail groove 50 within which is guided a slide 51 having upstanding ears 52 serving as journals for a rock shaft 53 carrying rock arms 54 connected by means of links 55 with the ends of the 115 cross shaft 49. A loose collar 56 on the rock shaft 53 is provided with an interiorly threaded sleeve 57 within which is screwed a tie rod 58 slidably within a bore 59 of the cross shaft 49 and having a head 60 120

which bears upon the opposite side of said shaft.

Affixed to the rock shaft is a lever 61 by means of which the said shaft may be rocked. The slide 51 is moved inwardly and outwardly by means of a screw spindle 62 squared at its outer end and having a threaded engagement at its inner end with the machine frame at 63.

- 10 If it be desired to adjust the position of the guide 47 to the finishing of a thicker piece of stock, the clamp rod 44 is released by means of the lever 45, leaving the frame 43 free to slide upon the casting 42. By means 15 of the hand lever 61 the shaft 53 is rocked and by means of the link connection with the ears 48 the frame 43 is drawn outwardly, the cross shaft 49 sliding upon the tie rod 58, until the guide 47 is brought to the exact 20 position desired. The frame 43 carrying the guide 47 is now locked to the casting 42 by the clamp rod 44 and the lever 45. The screw spindle 62 is thereupon turned, moving the slide 51 with its ears 52 outwardly until 25 the head 60 of the tie rod contacts with the shaft 49 indicating a proper distance between centers of the shafts 49 and 53, completing the adjustment of the guide rail.

- If it be desired to lessen the distance between the guide rail 47 and the cutter head 15 to act upon thinner stock, the clamp is again released by means of its lever 45, the screw spindle 62 is actuated to move the slide 51 and the frame 43 inwardly, the links 55 30 being straightened, until the guide 47 is nearer the cutter head 15 than the desired adjustment. Thereupon the lever 61 is employed to retract the guide 47 by means of the links 55 until it reaches the precise position 35 desired. It is here locked by means of the lever 45 and then the screw spindle 62 is retracted until the head 60 of the tie rod 58 contacts, as before, with the shaft 49, indicating the proper distance between 40 centers of the shafts 49 and 53, and thus completing the new adjustment of the guide.

- In case of emergency, the guide 47 may be quickly withdrawn by pushing the lever 45 downward to unclamp the guide-carrying 45 frame and then pulling upon the lever 61 to withdraw the guide and frame by means of the links 55. After the emergency has passed, the guide may be accurately positioned as before by pushing the lever 61 inwardly to straighten the links, and then lifting the lever 45 to clamp the parts rigidly 55 in position.

- Having reference to Figs. 2 and 4 of the drawings, it will be observed that each of 60 the feed rolls 12 is mounted to yield towards and from the associated feed roll 13, being drawn towards the roll 13 by means of the spring 64 upon rod 65 pivoted at 66 to the roll shaft bearings 12^b which, in turn, is 65 pivoted at 68 to the yoke 67, allowing the

upper ends of the feed roll shaft together with the roll 12 to swing about the pivot 68. Each of the feed rolls 12 is driven from the power shaft 69 by means of the bevel gear 70 in mesh with a similar gear 71 carried by 70 a countershaft 72 carrying a pinion 73 in mesh with a pinion 74 on the shaft 75 of the feed roll, while each of the feed rolls 13 is driven from the countershaft 72 by a pinion 76 in mesh with a pinion 76' driven 75 by pinion 77 on said countershaft.

The rearward swinging motion of the roll bearing 12^b is resisted by the spring 64 acting upon the collar 64^a and adjusted by the lock nuts 65^a. In case of need, the roll bearing 12^b and with it the feed roll 12 may be quickly withdrawn from the feed roll 13 by releasing the engagement of the spring 64 after the same manner described with reference to the spring 23 for the first guide. As 80 an abutment during assemblage and when the spring 64 is released a set screw 78 is provided the inner end of which is adapted to contact with the abutment 79 on roll bearings 12^b. 90

The assemblage of the yoke 67 with reference to the machine frame is most clearly illustrated in Figs. 9 and 11 having reference to Figs. 1, 4 and 8. A lug 80 carried by the yoke 67 and projecting within an opening 81 of the machine frame is acted upon at both sides by the heads 82 of bolts 83 threaded into the frame at 84 and provided with lock nuts 85. By this means the adjustment 95 of the yielding feed roll 12 with relation to the fixed feed roll 13 is primarily adjusted through the positioning of the pivot point 68, depending upon the yielding action of the springs 64 to impart the proper pressure 100 from the rolls upon the interposed material. 105

After leaving the finishing cutter head and passing between the feed rolls 12 and 13 the material is firmly held for presentation to the cutter heads (not shown) for tonguing and grooving or otherwise finishing the edges, by means of a guide plate 86 (Fig. 10) mounted upon the slide 87 housed within the frame 88 and spring-pressed forwardly by means of the spring 89 which is adjustable by means of the threaded collar 90 upon the spindle 91, the position of the threaded collar being maintained by means of the set screw 92. A lug 93 upstanding from the slide 87 provides for a limitation 110 of the movement of said slide which is adjustable by means of the set screws 94. 115

We claim:

1. In a machine of the character described, a cutter head, a stock abutment rail opposed to the operative face thereof, stock guides disposed one in advance and the other at the rear of the cutter head, means to yieldingly press both guides towards the abutment rail, and means to adjust the forward limit of movement of the second guide, said last 120

mentioned guide and mount including a slide carrying the guide, a second slide, a yieldable connection therebetween, and means for adjusting position of the second slide to determine the operative position of the guide.

2. In a machine of the character described, a cutter head, a stock abutment rail opposed to the operative face thereof, stock guides disposed one in advance and the other at the rear of the cutter head, means to yieldingly press both guides towards the abutment rail, and means to adjust the forward limit of movement of the second guide, said last mentioned guide and mount including a slide carrying the guide, a second slide, an operative connection therebetween comprising a bolt threaded in one slide and movable in the other, a compression spring on said bolt connection, and a screw spindle rotatably mounted in the second slide but axially fixed relatively thereto and threaded in a fixed support.

3. In a machine of the character described, a cutter head, a fixed abutment rail opposed to the operative side thereof, a movable stock guide at one side thereof, a suitably anchored spring pressing said guide towards the abutment rail, and means to release said spring to permit the withdrawal of the guide, a second adjustable stock guide mounted at the other side of the cutter head and yieldingly pressed towards the abutment rail, said last mentioned guide and mount including a slide carrying the guide, a second slide, a connection therebetween comprising a bolt threaded in one slide and movable in the other, a compression spring on said bolt connection, means for adjusting the tension of the spring, and a screw spindle provided with a handle and rotatably mounted in the second slide but axially fixed relatively thereto and threaded in a fixed support.

4. In a machine of the character described, a machine bed, a cutter head mounted thereon, a stock guide opposed to the operative face of the cutter head, and an adjustable and releasable mounting for the guide comprising a guide-carrying frame having a sliding connection with the bed, means to releasably clamp the frame to the bed, a slide having a guiding connection with the bed, a rock shaft journaled in one of the sliding members and having an arm and link connection with the other sliding member, and a lever for rocking the shaft.

5. In a machine of the character described, a machine bed, a cutter head mounted thereon, a stock guide opposed to the operative face of the cutter head, and an adjustable and releasable mounting for the guide comprising a guide-carrying frame having a sliding connection with the bed, means to releasably clamp the frame to the bed, a

slide having a guiding connection with the bed, a rock shaft journaled in the slide, an arm and link connection between the rock shaft and the guide-carrying frame, and a lever for rocking the shaft.

6. In a machine of the character described, a machine bed, a cutter head mounted thereon, a stock guide opposed to the operative face of the cutter head, and an adjustable and releasable mounting for the guide comprising a guide-carrying frame having a sliding connection with the bed, means to releasably clamp the frame to the bed, a slide having a guiding connection with the bed, a rock shaft journaled in the slide, an arm and link connection between the rock shaft and the guide-carrying frame, a headed tie rod connecting the slide and frame and slidale in one of them, and a lever for rocking the shaft.

7. In a machine of the character described, a machine bed, a cutter head mounted thereon, a stock guide opposed to the operative face of the cutter head, and an adjustable and releasable mounting for the guide comprising a guide-carrying frame having a sliding connection with the bed, means to releasably clamp the frame to the bed, a slide having a guiding connection with the bed, a rock shaft journaled in the slide, an arm and link connection between the rock shaft and the guide-carrying frame, a headed tie rod connecting the slide and frame and slidale in the frame, and a lever for rocking the shaft.

8. In a machine of the character described, a machine bed, a cutter head mounted thereon, a stock guide opposed to the operative face of the cutter head, and an adjustable and releasable mounting for the guide comprising a guide-carrying frame having a sliding connection with the bed and having side members embracing the bed, means to releasably clamp the frame to the bed comprising a cam device engaging the side members, and a lever to actuate the cam device to press the sides of the frame and bed together, a slide having a guiding connection with the bed, a rock shaft journaled in the slide, an arm and link connection between the rock shaft and the guide-carrying frame, and a lever for rocking the shaft.

9. In a machine of the character described, a machine bed, a cutter head mounted thereon, a stock guide opposed to the operative face of the cutter head, and an adjustable and releasable mounting for the guide comprising a guide-carrying frame having a dovetail sliding connection with the bed and having side members embracing the bed, means to releasably clamp the frame to the bed comprising a bolt engaging the side members and a lever to actuate the bolt to press the sides of the frame and bed together, a slide having a dovetail sliding con-

nection with the bed, a rock shaft journaled in the slide, arm and link connections between the rock shaft and the guide-carrying frame, a headed tie rod connecting the slide and frame and slidable in the frame, and a lever for rocking the shaft.

10. In a machine of the class described, a machine frame, a cutter head, an adjustable guide for holding stock to the action of the cutter head, a feed roll effective to hold stock against the guide, a movable frame forming a shiftable support for the feed roll, means adjustable on the machine frame and cooperating with the movable frame 15 to limit its movement toward and from the guide, and yieldable means for urging the movable frame toward the guide.

11. In a machine of the class described, pairs of cooperating feed rolls for transmitting stock through the machine, a cutter disposed between pairs of such rolls for operation upon stock transmitted by them, a guide operable between said pairs of rolls for supporting stock to the action of said cutter, 25 adjustable means cooperating with said guide whereby the limit of its movement toward the cutter may be predetermined selectively, and manually operable means effective upon said guide whereby it may be 30 moved from the cutter and toward the cutter to the selected limit.

12. In a machine of the class described, the combination of a rotary cutter, a pair of cooperating feed rolls at each side thereof for transmitting stock past the cutter, a guide rigidly supported to hold work to the action of the cutter, yielding pressure means effective upon one roll of each pair to urge the same toward the guide, and quickly operable means supporting the guide whereby it may be retracted from the cutter.

13. In a machine of the character described, including a pair of feed rolls between which the stock passes longitudinally of the machine, means to adjustably and yieldingly position one of the rolls comprising a casting within which the shaft of the roll is journaled, said casting pivoted to swing in a transverse plane perpendicular to the path of the stock, a lug carried by the casting and projecting between portions of the machine frame, bolts oppositely threaded into the frame with their heads bearing on the two sides of the lug, and a releasable spring drawing the pivoted casting and its roll towards the other roll.

14. In a machine of the character described, a machine frame, a tool mounted thereon for acting on the stock, a stock abutment rail, a stock guide having its face in opposed spaced relation to the rail, a slide supporting the guide, means for varying the

limit of movement of the slide toward the rail, a spring bearing upon the slide to press the guide towards the rail, and means to adjust the tension of the spring without varying the limit of movement of the slide.

15. In a machine of the character described, a machine frame, a tool mounted thereon for acting on the stock, a stock abutment rail, a stock guide having its face in opposed spaced relation to the rail, a guide-carrying slide, means for varying the limit of movement of the slide toward the rail, a housing for the slide, a rod secured in the slide longitudinally thereof, a spring about the rod and bearing upon the slide to press the guide towards the rail, and means to adjust the tension of the spring without varying the limit of movement of the slide toward the rail.

16. In a machine of the character described, a machine frame, tools mounted thereon for acting on the stock, a stock abutment rail, a stock guide having its face in opposed spaced relation to the rail, and means to adjustably and yieldingly position the guide comprising a guide-carrying slide having a laterally projecting lug, a housing for the slide cut away to accommodate the lug, set screws seated in the housing and acting as abutments for each side of the lug to limit the range of movement of the slide, a recess in the rear end of the slide, a compression spring within the recess, and means to adjust the tension of the spring.

17. In a machine of the character described, a machine frame, tools mounted thereon for acting on the stock, a stock abutment rail, a stock guide having its face in opposed spaced relation to the rail, and means to adjustably and yieldingly position the guide comprising a guide-carrying slide having a laterally projecting lug, a housing for the slide cut away to accommodate the lug, set screws seated in the housing and acting as abutments for each side of the lug to limit the range of movement of the slide, a rod secured in the slide longitudinally thereof, a recess in the rear end of the slide, a compression spring disposed about the rod within the recess, and means to adjust the tension of the spring comprising a collar threaded on the rod as a rear abutment for the spring.

In testimony whereof we have hereunto signed our names in the presence of two subscribing witnesses.

CHARLES J. MARSHALL.
FRANK R. WEAVER.
